UNITED STATES PATENT OFFICE

138,344

DESIGN FOR A BELT

Basil Darrell Huff, New York, N. Y.

Application February 18, 1944, Serial No. 112,619

Term of patent 3½ years

(Cl. D3—10)

To all whom it may concern:

Be it known that I, Basil Darrell Huff, a citizen of the United States of America, residing in New York city, county of New York, and State of New York, have invented a new, original, and ornamental Design for a Belt, of which the following is a specification, reference being had to the accompanying drawing, forming part thereof.

The figure on the drawing is a perspective view of a belt showing my new design. The opposite side of the belt is substantially the same as the side shown.

I claim:

The ornamental design for a belt, substantially as shown and described.

BASIL DARRELL HUFF.
